UNITED STATES PATENT OFFICE.

CHARLES P. WALTER, OF HARRISBURG, PENNSYLVANIA.

RAILROAD-TIE.

No. 832,644.

Specification of Letters Patent.

Patented Oct. 9, 1906.

Application filed January 17, 1906. Serial No. 296,516.

To all whom it may concern:

Be it known that I, CHARLES P. WALTER, a citizen of the United States, residing at Harrisburg, in the county of Dauphin and State 5 of Pennsylvania, have invented a new and useful Railroad-Tie, of which the following is a specification.

This invention relates to railway-ties, and has for its object to improve the construction and increase the efficiency and utility of 10 devices of this character.

With these and other objects in view, which will appear as the nature of the invention is better understood, the invention consists in 15 certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical 20 operation.

In the drawings, Figure 1 is a side elevation, and Fig. 2 is a plan view, of the improved tie with the rails in position thereon. Fig. 3 is a perspective view of the improved tie.

The improved tie comprises metal side 25 plates 10 11 of the usual length of a railway-tie, generally about eight feet, and with spaced recesses 8 9 in the upper edges to receive the tie-flanges of the rails represented at 12 13. Disposed between the plates 10 11 at the end portions are cushion-blocks 14 15, 30 of wood or like material, secured by clamp-bolts 16 17, extending transversely through the plates and blocks, the blocks bearing beneath the rails and secured thereto by the usual spikes 20 21, and flush at the outer ends 35 with the outer ends of the plates and with the inner ends spaced apart, whereby an open space 18 is left between the inner ends of the blocks.

The blocks are formed with the portions 40 between the rails and their inner ends thicker vertically than the outer portions, whereby shoulders 22 23 are formed to bear against

the inner edges of the tie-flanges of the rails, and thus effectually prevent outward displacement of the blocks, while at the same time not preventing the withdrawal of the blocks inwardly. The lengths of the blocks 45 14 15 are less than the distance between the tie-flanges of one rail and the inner end of the 50 block of the outer rail, so that by removing the clamp-bolts 16 or 17 and spikes 20 or 21, as the case may be, the released block may be removed by simply drawing it inwardly into the space 18 and then withdrawing 55 it from between the plates 10 11. Thus when a block becomes worn or broken it can be readily renewed without disturbing the body of the tie or the rails or the tamping or bedding except sufficiently to expose the 60 clamp-bolts 16 or 17 and the small amount of ballast or paving above and within the space 18. The only labor required, therefore, is to remove a small amount of ballast or tamping and withdraw bolts 16 or 17 and the spikes 20 65 or 21, as heretofore noted.

The device is simple in construction, is strong and durable, and can be applied to any of the various railway constructions in use.

Having thus described the invention, what is claimed is—

A railway-tie comprising side plates spaced apart and provided with rail-receiving recesses, cushion-blocks secured between said 80 plates and bearing beneath the rails with the inner ends spaced apart and the portions between said inner ends and the rails thicker than the remaining portions, whereby shoulders are formed on the blocks for bearing 85 against the inner edges of the tie-flanges of the rails to enable the cushion-blocks to be removed without disturbing the rails or plates.

In testimony that I claim the foregoing as 90 my own I have hereto affixed my signature in the presence of two witnesses.

CHARLES P. WALTER.
